CLAIM

The ornamental design for a massage appliance, as shown and described.

DESCRIPTION

1. Massage appliance

1.1) Perspective;

1.2) Front;

1.3) Top; and

1.4) Bottom.

A massage appliance according to the present design comprises an elongated cylindrical casing, spherical head connected to the upper end and a cap attached to a lower portion of the casing main body; the back view, the right view and the left view appear the same as the front view, so they are omitted.

The broken lines disclose unclaimed portions of the massage appliance and form no part of the claimed design.
